UNITED STATES PATENT OFFICE.

RUFUS M. STIVERS, OF NEW YORK, N. Y.

DESIGN FOR THE BASES OF CARRIAGE-BODIES.

Specification forming part of Design No. 5,193, dated August 8, 1871.

To all whom it may concern:

Be it known that I, RUFUS M. STIVERS, of the city, county, and State of New York, have invented a new and original Design for Carriage-Body; and I do hereby declare that the following is a full, clear, and exact description thereof, which will enable others skilled in the art to make and use the same, reference being had to the accompanying drawing forming part of this specification, in which—

Figure 1 represents a side view of the carriage-body. Fig. 2 is a transverse section of the same on the line *e e*, Fig. 1.

This invention relates to a new ornamental design for the base of carriage-bodies; and consists in applying a rib or molding to the base edge of a carriage-body so as to conceal the body-loops attached to the bottom of said body.

A in the drawing represents the base of a car-

riage-body, and B B the body-loops attached to the under side of and designed for supporting the same. *a* indicates a rib, molding, or downward extension of the carriage-body. The width of the ribs or distance to which they extend downward may be varied according to the thickness of the loops, it being only essential that they cover or conceal said loops, as clearly shown in Fig. 2.

It will be understood that my design has no reference to aught save the base edge of the carriage-body.

What I claim is—

The ornamental design for the base of a carriage-body, as shown and described.

RUFUS M. STIVERS.
